(57) **CLAIM**

The ornamental design for a bottle, as shown and described.

DESCRIPTION

FIG. 1 is a front elevational view of the bottle embodying the present invention;

FIG. 2 is a rear elevational view of the bottle;

FIG. 3 is a side elevational view of the bottle;

FIG. 4 is an opposite side elevational view of the bottle;

FIG. 5 a top plan view of the bottle; and,

FIG. 6 is a bottom plan view of the bottle.

The broken line showing of the bottom of the bottle is for illustrative purposes only and forms no part of the claimed design.
